(57) **CLAIM**

The ornamental design for a retractable pet leash housing, as shown and described.

DESCRIPTION

FIG. 1 is a front and left perspective view of the new design for a retractable pet leash housing.

FIG. 2 is a rear and right perspective view of the new design of FIG. 1

FIG. 3 is a front and right perspective view of the new design of FIG. 1

FIG. 4 is a rear and left perspective view of the new design of FIG. 1

FIG. 5 is a right side elevational view of the new design of FIG. 1

FIG. 6 is a left side elevational view of the new design of FIG. 1

FIG. 7 is a top plan view of the new design of FIG. 1

FIG. 8 is a bottom plan view of the new design of FIG. 1

FIG. 9 is a rear elevational view of the new design of FIG. 1; and,

FIG. 10 is a front elevational view of the new design of FIG. 1.

In the figures, the thinner solid lines appearing within the boundaries of the retractable pet leash housing are shading lines used to indicate the shape and location of the surfaces. The broken lines in the figures are shown for purposes of illustrating environmental structure and form no part of the claimed design.
